UNITED STATES PATENT OFFICE.

SAMUEL C. LANCASTER, OF SEATTLE, WASHINGTON.

DUMPING-VEHICLE.

1,047,249.

Specification of Letters Patent. Patented Dec. 17, 1912.

Application filed October 18, 1910. Serial No. 587,712.

To all whom it may concern:

Be it known that I, SAMUEL C. LANCASTER, citizen of the United States, residing at Seattle, Washington, have invented certain new and useful Improvements in Dumping-Vehicles, of which the following is a specification.

My invention relates to dumping vehicles, one object being to provide a supporting structure for balancing or pivotally supporting the buckets or receptacles preferably at intermediate points in their length to render their manipulation easy and certain in both opening and closing.

A further object of my invention is to provide an arrangement of bucket and supporting frame in which the latter will form the bottom wall of the bucket and partially sustain the material, the bucket moving away therefrom in opening to discharge the material.

Another object is to provide a pair of buckets, each pivotally supported preferably at an intermediate point in its length and operated by connections to the adjacent or inner ends of the buckets which lowers or raises these adjacent ends to effect the opening and closing actions.

Another object is to provide a pair of buckets with supporting frame work between them adapted to receive and support driving mechanism, and other objects of my invention will appear from the following description.

The invention consists in the features and combination and arrangement of parts hereinafter described and particularly pointed out in the claims.

In the accompanying drawings, Figure 1 is a side view of one form of vehicle embodying my invention; Fig. 2 is a sectional view taken longitudinally of the vehicle of Fig. 1; Fig. 3 is a plan view of the vehicle of Fig. 1 with a portion broken away; Fig. 4 is a transverse sectional view through a vehicle of the form shown in Fig. 1 embodying my invention; Fig. 4^a is a side view of a bucket detached; Fig. 4^b is a side view of a side plate; Fig. 5 is a detail view of one way of applying a motor to the vehicle, it being understood, however, that the vehicle may be of various forms and driven or drawn in different ways; Fig. 6 is a side view of two vehicles such as shown in Fig. 1 coupled together to make a composite vehicle, and which may be used at the head of a train of

vehicles such as is shown in Fig. 1, or may be used in other relations; Fig. 7 is a side view of a train of vehicles of the form shown in Fig. 1 with a car or truck at the front for carrying a generating set and controller mechanism; Fig. 8 is a plan view of Fig. 7; Fig. 9 indicates that certain features of my invention may be embodied in another form of vehicle having two large carrying wheels and a truck wheel for steering, this vehicle carrying its own source of power, its own motor and controller; Fig. 10 indicates one way in which my invention may be embodied in a horse drawn vehicle. Figs. 11 and 12 are views relating to one form of the carrying wheels. Figs. 13 and 14 are views relating to a wheel construction.

In the drawings, 1 indicates triangular shaped frames, one on each side, made up of angle irons 1' converging upwardly and riveted together at their upper ends and connected at their lower ends by a horizontal angle iron 1''. The inclined angle irons are further connected by a horizontal angle iron 2, one on each side at points near their converging upper ends. These frames support the buckets as will be hereinafter described, and they are hung in a main frame 3 composed of an angle iron extending horizontally on each side of the apparatus, and having curved ends at front and rear. For hanging the triangular supporting frames in this main frame, I provide springs 4 and bolts 5, the said springs bearing on the under side of the strut, and the bolts passing through the strut with nuts or heads on their ends above the strut. The lower ends of the springs bear upon brackets 6 at the journal boxes 7, in which the axle 8 is supported, said boxes being supported on the main frame 3 and the said axle having the carrying wheels 9 secured thereto.

In addition to the springs 4 or in place thereof the supplemental frame may be supported yieldingly by leaf springs 4' one at each side, which are clipped to the axle and which are connected at their ends to the supplemental frames.

The triangular frame on one side of the machine is connected with that on the other side of the machine by transversely extending angle bars 10 at their lower corners and at their apex by a transversely extending V shaped angle bar 10' having its apex directed upwardly.

Between the triangular side frames plates

- 10" extend which are riveted to the inclined angle irons and form the fixed bottom of the receptacles for holding the material of which the buckets form the movable parts.
- 5 On the other lateral sides of the triangular frames I secure side plates 11, one at each side of the machine, each riveted to one of the triangular frames and these side plates are of general triangular form and extend
- 10 across the opening within the triangular supporting frame forming side closures therefor, and extending beyond the inclined angle irons to form side guides for the movable buckets within which the buckets move.
- 15 The upwardly converging plates 10", together with the side plates 11, and with a bottom plate 11^a form a housing for a motor and transmission arranged in the space within them, as will be described herein-
- 20 after, and this bottom plate is provided with a door 11^b whereby access may be had to the interior of the housing.

The buckets are composed of side plates 12, and curved end plates 13, each being strengthened by angle iron bars 14, riveted along the top edges of the buckets and along their curved end edges, and also across their lower edges as at 16. The buckets are hung on pivots 17 intermediate of their length, said

25 pivots being carried upon links or swinging bars 18 pivoted at their lower ends to the corners of the triangular frames. The buckets are dumped by depressing their adjacent inner ends, for which purpose each has at its

30 inner end an ear or extension 19 overlapping the ear on the other bucket, and these ears are pivotally connected together at 20. At the meeting inner ends of the buckets on each side, a yoke piece 21 is pivoted extending

35 on the outside of the side plates 11, and each connected at its ends by a pin and slot at 22 with the upper inner ends of the buckets. The yoke plate is of angle iron and it carries a pin at 23 guided in a slot 24 in a vertical hanger 25 lying outside of the side plates 11 and at a slight distance therefrom to admit a link 26 between it and the side plate, which link is connected to an arm 26' on a transverse shaft 27 bearing in

40 the lower ends of the hangers, and in the side frame plates 11. This shaft has an operating lever 28 connected thereto. The hanger 25 has at its upper end an inwardly projecting head which is recessed to fit over

45 the upper apex of the side plate. This construction is duplicated at the other side of the machine, though only one operating handle or lever 28 is used.

In order to dump the buckets, the handle

50 or lever 28 is lifted, and through the connections described the inner ends of the buckets are depressed, causing them to turn on the pivots 17 of the supporting links or bars 18 and throwing their lower ends away

55 from the central saddle-like frame, and the

inclined bottom plates 10" connected thereto, so that the material can slide down by gravity through the openings thus provided. In this action the connecting yoke will move vertically, being guided by the pin and slot connection, and the pin and slot connections at 22 will draw down the inner ends of the buckets. The links 18 will swing inwardly slightly. When the buckets are closed, they may be held in this position by a catch 28^a, 70 engaging the operating lever, and this lever can be released by forcing it down and laterally slightly. As another means of locking the buckets closed, I may use a pin 19^a passing through one of the ends of the 75 buckets or their extensions and the yoke and side plate, and this pin may be left in place when the vehicle is on a run of considerable distance. When the buckets are closed, the weight of the material will be sustained by 80 the inclined bottom walls 10 and the curved end walls 13, and with the buckets locked together and their meeting ends held up, the intermediate pivot bearings of the buckets will be relieved from strain. Dumping can 85 be effected by the application of little power to the hand lever 28 after this is released, and the locking pin, if used, is removed, because in dumping, each bucket is balanced on the pivots intermediate of its length, and 90 it requires but little force applied to the meeting ends of these buckets to depress them at this point and cause them to open. It will be observed also that the bucket is 95 hung to have approximately a rotary movement in respect to the pivots 17, and in closing by raising the inner end of the bucket a slight lifting movement is given to the lower end of the bucket instead of a direct movement toward the central frame, 100 so that the discharge of the material can be readily cut off with the application of little power. Attention in this connection is called to the relation of the angle iron at the lower edge of the bucket in respect to the 105 angle iron at the lower end of the central frame, these angle irons forming wearing members and that on the bucket having a movement edgewise, nearly at right angles to the opposing surface of the other iron, 110 so as to cut through the material in closing.

The interior of the buckets is entirely clear, no rods or other members extending across them to obstruct the space or to be subject to injury or wear from contact of the material therewith when delivered into the bucket. The cross shaft 27 extends through the space within the central frame, and is thus protected, and this space may be utilized for receiving any suitable driving 115 mechanism, for instance, an electric motor indicated conventionally at 29. Any suitable form of differential gearing may be combined with the axle when this axle, as in the present case, is a live one, and divided 120

for purposes of turning, and this mechanism indicated conventionally at 29' may be located in the space within the frame.

As before referred to, the plates connected with the triangular frames form a housing for the motor and driving gearing, and this protects the inclosed parts from dust and weather. By tipping the vehicle, the bottom of the supplemental frame will assume an inclined position, so that the lower door may be readily removed and access had to the interior of the frame, and the parts housed therein. The bucket frame, in its resilient vertical movement allowed by the springs, is guided by angle bars 30 secured to the side plates and working against guide blocks 30' fixed to the main frame.

As before stated, the main frame is composed of angle iron presenting a horizontal flange or ledge at its interior bottom edge, and at the curved ends of this frame draw-bars 31 rest on the horizontal flanges, being pivoted at 32 to cross bars 33 on the main frame. These draw-bars have brackets or boxes 34 riveted to their under sides which receive bolts 35 connected with draw heads 36, springs 37 being interposed between the boxes and collars 38 on the bolts. The draw-bars are adapted to slide on the semi-circular ends of the main frame according as the line of draft shifts and the spring draw head provides accommodation for unevenness in the roadway over which the vehicle is being drawn, it being understood that a number of these vehicles can be coupled together in a train and be drawn by a motor car at the front, the spring draw head being free to assume different angular positions in passing over uneven places. It will be understood also that each vehicle may be supplied with an independent motor and battery thereon and one or more of these may be operated to drive the entire train, or the vehicles may be used individually and be horse drawn if desired.

I have also provided a brake for the vehicle consisting of bands 39, 40, applied to drums 41, carried by the wheels. These bands, a pair being used for each wheel, are connected by pins or bolts to blocks 42 supported on the frame and their other ends are connected to a brake lever 43 on each side of the pivot 44 thereof. The brake lever, on one side, is connected with that on the other side by a cross bar 45. The cross bar is connected with a rope 46 by which the brake is held off, but when this is released, the lever will fall and set the brake. The brakes of the several vehicles in a train may be connected with the one rope as in Fig. 7 so that should any vehicle become detached from the rest of the train, all of the brakes throughout the series of vehicles will be set by the falling of their brake levers. The rope 46 passes around a pulley 47 on the brake lever.

ver, and about a pulley 48 on a standard 49 supported on the main frame, the said rope being looped about these pulleys, as shown, and extending from car to car. A spring or weight may be used to insure setting the 70 brake, this being connected with the brake lever.

I do not limit myself to the details of construction above described, as these may be varied without departing from the principle 75 of my invention, and as indicating that the invention may be applied in various ways, reference is made to Fig. 9, in which the main frame is mounted upon a wheel or wheels indicated at 50 at the front of the 80 frame which frame extends farther forward than in the form first described, and where, as in the example shown, one wheel at the front is used, this may answer as the steering 85 wheel; being connected with the steering post 52. A seat for the driver is provided at 53, and the lever for dumping the buckets extends in proximity to this seat to be operated by the driver, who can steer, dump, and, through a suitable controller, he can 90 control the drive. This drive in this form may consist of a motor connected with the shaft 53' and mounted in the body. This shaft is connected by a chain 54 with a drive wheel 54' on the axle of the larger rear 95 wheels. The buckets are arranged in a manner similar to those above described, and the supplemental frame carrying these buckets is spring mounted, and is guided in its vertical movement by the angle iron bars 30, the 100 rear one, however, working against the rear end of the frame.

In Fig. 10 I show the application of my invention to a horse drawn vehicle, a pair of small wheels being used at the front connected with the body by a fifth wheel, and a draft pole being connected with the axle. In this form the main frame 3' is extended to the rear and another vehicle may be attached to this extension to be drawn along 110 therewith.

In another form of my apparatus, *i. e.*, like a cart, I may prefer to use a motor in each of the two wheels, and as a type of motor and transmission which may be used for this purpose, I would refer to that shown in the patent of Church and Knudsen, dated June 11, 1907, #856,943, and these motors can be controlled independently, either being cut out or reduced in speed for turning. 115 So far as this part of my invention is concerned, I do not limit myself to any particular form of drive for the wheels of the cart, mentioning the Knudsen motor and transmission as one that might be used for the purpose, my invention, in this respect, being broader than the particular means used, for so far as I am aware, it has not been previously proposed to provide a cart 120 having driving mechanism for each wheel 125 130

and each capable of being controlled independently of the other so that no steering apparatus is necessary independent of or additional to the drive, the latter performing the twofold function of propelling and steering the vehicle according to the relative speeds of the independent drives or motors, suitable controlling devices well known in the art controlling the current to either 10 wheel. When such a cart is used at the head of a train for steering as well as propelling, it will carry a battery within its triangular frame and a controller, which may be arranged on a suitable support indicated at 15 60 in Fig. 6, wherein also the driver's seat is shown. This controller will control the steering by the wheels of the front cart by reducing the speed of one in relation to the other, or stopping or reversing one while 20 the other continues to drive, and as each of the other carts of the train may have its own motor or motors whether in the wheels or in the housing, and also its own battery, suitable controlling means will be arranged 25 on the front cart for controlling these motors for forward driving. The front cart will be coupled to the second cart to make a composite vehicle composed of these two carts coupled together. The coupling, however, will be locked against lateral swinging movement in respect to the first cart, for which purpose I provide a pin 59 to pass down through an opening in the bar 31, as shown in Figs. 1 and 6, and into an opening 30 in the end of the main frame. This will hold the coupling to the frame of the first cart, thus providing, in effect, a tail bar or piece on the front cart held centrally against lateral movement extending rearwardly and 35 pivoted to the rear cart at 32, because these two couplings are rigidly connected together at their meeting heads, and by this arrangement the second cart is led by the first cart in such manner as to track therewith, it being understood that the coupling bar is not 40 locked or pinned to the front of the second cart, but can turn laterally in respect thereto, while drawing it forward. Between the other carts of the train the draw-bars 31 45 are locked or similarly pinned in place at the rear of each cart to form rigid tail pieces extending rearwardly, and pivotally connected with the next cart to lead the same and cause tracking thereof with the 50 cart next in front. As the carts are reversible end for end, openings are provided in the draw-bars and in the main frames at each end of each cart to enable either draw-bar to be pinned in place against lateral movement, but when connected up in a train only 55 the rear draw-bar of each cart is pinned against lateral movement.

I have also provided an improved form of wheel particularly adapted for heavy haul- 60 ing and road building, which will avoid

breakdowns due to crystallization of the spokes and which may be repaired with ordinary facilities and tools. The rim of the wheel is formed of stock channel iron, the spokes of wooden beams rectangular in cross section, such as may be provided from stock timber or scantling. The outer ends of these fit in cast sockets riveted to the rim and at their inner ends they fit against blocks 55, one for each spoke, said blocks bearing on wedges 56 movable laterally of the wheel, and being operated by the screws 57. These have nuts on one end and heads on the other by which the screws are turned for adjusting the wedges. The wedges 56 70 at their inner ends bear on the hub of the wheel. The bolts pass through a plate or flange 57' on the inner side of the wheel formed with or fixed to the hub, and this plate may carry the drum for the brake 75 band. The bolts also pass through a face plate 58 at the outer side of the wheel. By removing the nuts, the face plate may be removed and access had to the wedges and spokes, and either one may be removed and 80 replaced, and when the wheel is complete, any spoke can be adjusted individually. The bolts indicated at 57 pass between the 85 spokes and through the plates. The inner ends of the spokes are squared off and the 90 blocks 55 serve as wearing shoes to receive 95 the pressure from the wedges.

While I have described the buckets as being pivoted at their upper ends intermediate of their length, I do not limit myself 100 to any particular position for these pivots in respect to the length of the buckets, and, indeed, the pivots may be placed at the front of the forward bucket and at the back of the rear bucket.

I have described and shown several specific forms of my invention with a view to indicating that the scope of my invention is not limited to any one form of apparatus, and in this connection I desire to state that 110 divisional applications will be filed for the specific forms and features disclosed herein, but which it is not possible to claim under the rules in this application.

Reverting to that part of my invention 115 relating to the use of the carts in trains, the train of carts can be run in either direction, it being necessary only to shift the pins which fix the coupling bars to the other ends of said bars to secure the tracking above described. Where a generating set is used this can be shifted from one end of the train to the other. Instead of a generating set a traction engine may be used to draw the 120 train of carts.

Fig. 13 shows one of the wooden blocks used to form the tread of the wheel, these being placed side by side with their wider lower portions fitting under the flanges of the rim.

As shown in Fig. 14 I may employ the rim of the wheel as the tread, the flanges of the angle iron projecting in this case inwardly and the sockets for the spokes being arranged or fixed in the channel of the rim.

5 I claim as my invention:

1. In a dumping vehicle, the combination of a saddle-like frame, carrying wheels, a pair of fore and aft buckets surmounting said frame one at the front and one at the rear of said frame, and mounted to turn on pivots at their upper portions out beyond their adjacent ends, and means for lowering and raising the upper adjacent ends of the buckets to open and close them in respect to the intermediate saddle-frame, substantially as described.
2. In a dumping vehicle, the combination of a saddle-like frame, carrying wheels, a pair of fore and aft buckets surmounting said frame one at the front and one at the rear of said frame, links pivotally connected to the frame at their lower ends, and extending upwardly and pivotally connected to the buckets, and connections for lowering or raising the adjacent inner ends of the buckets causing the lower ends of the buckets to move from and toward the saddle-like frame, substantially as described.
3. In combination in a dumping vehicle, a saddle-like frame, a pair of buckets surmounting the same, one at each side, each pivotally mounted upon a shifting pivot, said buckets being pivotally connected with each other at their inner ends, a yoke piece having shifting pivot connections with the adjacent ends of the buckets, means for raising and lowering the yoke piece, and carrying wheels for the frame, substantially as described.

4. In combination in a dumping vehicle, a saddle-like frame, a pair of buckets surmounting said frame one at each side, each pivotally mounted, a yoke piece connecting the inner or adjacent ends of the buckets, a guide connected with and extending up from the saddle frame for the vertical movement of said yoke piece, means for moving the yoke piece vertically, and carrying wheels for the frame, substantially as described.

5. In combination in a dumping vehicle, a saddle-like frame with carrying wheels, a pair of buckets surmounting the same one at the front and one at the rear of the said frame, and movable toward and from the said frame about pivots out beyond their adjacent ends, and means for operating the said buckets simultaneously, said means drawing the adjacent ends of the buckets toward the frame for opening the buckets, substantially as described.

6. In combination in a dumping vehicle, a frame having plates inclining downwardly and away from each other, and a pair of

buckets, one fore and the other aft of said frame, and of which the inclined frame plates form the bottoms, means for moving the buckets toward and from their bottom plates, springs on which the frame is mounted, a main frame, and carrying wheels, substantially as described.

7. In combination in a dumping vehicle, a main frame, supporting wheels, a triangular shaped frame mounted in the main frame, springs between the triangular frame and axle, a bucket at the front and rear of the triangular shaped frame, means for operating the buckets, and means for guiding the triangular shaped frame in its movement, substantially as described.

8. In combination, a main frame, a supporting axle and wheels, a triangular shaped frame mounted in the main frame, springs for supporting the triangular frame, a bucket at the front and rear of the triangular shaped frame, and means for guiding the triangular shaped frame in its movement, and driving means in the space within the triangular shaped frame, substantially as described.

9. In combination in a dumping vehicle, a main frame, a supplemental frame yieldingly mounted, buckets carried by the supplemental frame, means for operating the buckets, and carrying wheels, substantially as described.

10. In combination a main frame, carrying wheels, a spring mounted supplemental frame, buckets in front and rear of the supplemental frame and supported thereby, and a motor supported within the supplemental frame for driving the vehicle, substantially as described.

11. In combination a main frame, a spring mounted supplemental frame of triangular form, inclined buckets at the front and rear of the supplemental frame, carrying wheels, an axle therefor passing through the space within the supplemental frame, a motor within said frame, and a connection between the same and the axle, substantially as described.

12. In combination in a dumping vehicle, a pair of buckets, a frame between them and which is surmounted by said buckets, said frame having plates inclosing the same to form a housing, a motor or driving means within the housing, and supporting wheels for the vehicle, substantially as described.

13. In a dumping vehicle, a pair of buckets, a frame between them forming a housing, driving means for the vehicle within the housing, said frame being tiltable, and a door in the bottom of the housing to permit access thereto when tilted, substantially as described.

14. In combination in a dumping vehicle, a saddle-like frame having fore and aft plates diverging downwardly, fore and aft

6
buckets, one on each side of the frame pivoted at their upper portions out beyond their adjacent ends, and having respectively their front and rear walls converging with the plates of the frame, means for raising and lowering the adjacent ends of the buckets, and carrying wheels, substantially as described.

15. In combination in a dumping vehicle, carrying wheels, a saddle-like frame having fore and aft plates diverging downwardly, fore and aft buckets surmounting the said

frame pivoted at their upper portions and having respectively their front and rear walls converging with the fore and aft plates 15 of the frame, and means for moving the buckets on their pivots, substantially as described.

In testimony whereof, I affix my signature in presence of two witnesses.

SAMUEL C. LANCASTER.

Witnesses:

BENNETT S. JONES,
WALTER DONALDSON.
